(57) **CLAIM**

The ornamental design for a combined hoodie-hat, as shown and described.

DESCRIPTION

FIG. 1 is a perspective view of the combined hoodie-hat; FIG. 2 is an alternate front perspective view of the combined hoodie-hat showing the hat turned in the opposite direction; FIG. 3 is a front perspective view of the combined hoodie-hat showing the hat removed from the hoodie;

FIG. 4 is a front view thereof;

FIG. 5 is a rear view thereof;

FIG. 6 is a side view thereof; and,

FIG. 7 is a top view thereof.

The broken lines shown throughout the views of the combined hoodie-hat, which are immediately adjacent to claimed surfaces, represent the bounds of the claimed design, while all other broken lines are directed to the environment and are for illustrative purposes only; the broken lines form no part of the claimed design.
